UNITED STATES PATENT OFFICE.

WILLIAM S. ELLIOTT, OF PITTSBURG, PENNSYLVANIA.

ELASTIC-FLUID TURBINE.

No. 806,073.

Specification of Letters Patent.

Patented Nov. 28, 1905.

Application filed May 26, 1904. Serial No. 209,927.

To all whom it may concern:

Be it known that I, WILLIAM S. ELLIOTT, a citizen of the United States, residing at Pittsburgh, in the county of Allegheny and State of Pennsylvania, have invented certain new and useful Improvements in Elastic-Fluid Turbines, of which the following is a specification, reference being had therein to the accompanying drawings, forming part of this specification, in which—

Figure 1 is a partial end view of an elastic-fluid turbine provided with my improved valve-controlled apparatus. Fig. 2 is a vertical sectional view on the line II II of Fig. 1. Fig. 3 is a detail view similar to a portion of Fig. 1, showing a plurality of nozzles controlled by a single valve. Fig. 4 is a vertical sectional view on the line IV IV of Fig. 1. Fig. 5 is a horizontal cross-sectional view taken on the line V V of Fig. 4.

The object of my invention is to automatically govern the supply of fluid to an elastic-fluid turbine, so as to maintain uniform speed under varying loads, by means of a series of nozzle-valves and their controlling mechanism, in combination with means for automatically controlling the admission of fluid to the vanes in a varying volume supplemental or in addition to the volume passing through said one or more nozzle-valves. For this purpose I employ a governor-controlled valve operating in conformity with varying engine speeds, in combination with the nozzle-valves, so designed that it will supplement the admission through any one of said nozzle-valves and regulate the flow intermediate of any two such adjacent valves, thus maintaining the engine in equilibrium and delicately regulating the supply at all times in conformity with the varying loads.

The governor-controlled valve is fully described and conforms to subject-matter of a companion application, (D.) filed April 8th, 1904, bearing the Serial No. 202,160.

Referring now to the drawings, 2 is the shell or case of the turbine, surrounding the wheel 3, mounted on the usual shaft 4 and provided with the customary vanes 5.

6 is an elastic-fluid chamber having a supply connection 7 extending out beyond the engine at any suitable position, as indicated in Fig. 1, by which elastic fluid is supplied to the various valve-controlled nozzles leading to the vanes of the turbine wheel or wheels.

55 At intervals located in the interior of cham-

ber 6 are a number of valve-seated nozzles 8, leading to the vanes 5, each of said nozzle-seats being provided with a valve 9, mounted on the inner end of stem 10, passing out through a stuffing-box. Each stem 10 is provided with a piston 11, mounted in a cylinder 12, an interposed spring 13 being provided surrounding the stem 10, adapted to bear against the piston, so as to unseat the valve when pressure is relieved from the piston. 65

Means are provided by which pressure is applied to one or more of the pistons 11, as follows: Mounted in a suitable position is a cylinder 14, to which constant fluid-pressure is supplied by connection 15, while pipes 16 connect each of the cylinders 12 with the interior of the cylinder 14 and are adapted to supply constant pressure against such of the pistons 11 to which said constant pressure is maintained. 75

17 is a valve mounted in cylinder 14 on the end of a stem 18, projecting into a supplemental cylinder 19 of a diameter or area greater than cylinder 14 and provided with a correspondingly larger piston 20. 80

The inner ends of pipes 16 communicate with the interior of cylinder 14 by ports 21, through which the pressure from pipe 15 is communicated to the pistons 11 when the inlet ends of such inner ports 21 are uncovered 85 by piston-valve 17. Communicating with such inlet-ports 21, either by a diagonal groove or by other suitable passage, are terminal ports 22, so located that when the inlet-ports 21 are covered by the advancing piston-valve 17 the ports 22 or the other end of the groove will become uncovered. By this construction the exhaust from the cylinder 12 is delivered behind the piston-valve 17 and escapes through an exhaust-pipe 23, connected 95 with the cylinder.

Beyond the piston 20 the cylinder 19 is provided with an inlet-port 23, controlled by valve 24, and an outlet-port 25, controlled by valve 26, mounted on the ends of stems 27 and 28, respectively. These stems are pivotally connected to the outer extremities of yoke 29, which is mounted at its center upon pins 30, with which it makes slotted engagement to allow free movement of the yoke. 105 The pins 30 are connected with or form a part of the vertically-movable portion of a centrifugal governor A, geared by bevels 31 from the main shaft or in any other suitable manner usual with this class of devices. A cush- 110

ion-spring 32 is inserted between valve 24, by which it is normally held in closed position to shut off the supply of fluid to the cylinder 14, while a similar spring 33 is inserted above valve 26 and adapted to normally close port 25 to cut off the exhaust therefrom.

The constant fluid-pressure acting on piston 17 and also on the piston 11 of the nozzle-valve stems may be supplied from the same source which supplies the turbine, and preferably at the same pressure.

The valve-regulating mechanism just described forms the subject-matter of a separate application bearing the Serial No. 196,195.

15 In a companion application bearing the Serial No. 193,556 I have shown and described a different mechanism for regulating the admission of fluid to the nozzle-valves through the operation of a cam-bar adapted to actuate the 20 valve-levers actuated by pistons subject to variable pressure. This construction may also be employed to control the nozzle-valves of the present invention.

The present invention is designed to provide 25 means for supplying a varying volume of fluid to the vanes independent of any supplemental to the uniform volumes supplied through the nozzle-valves, so as to regulate the fluid-supply for variations in the load between any two consecutive nozzle-valves. To this end I have employed a governor-controlled valve admitting a pulsating supply similar in construction and operation to the controlling-valve shown and described in companion application bearing the Serial No. 30 202,160.

An independent valve-seated nozzle 38 (or for multiple or stage expansion engines two or more of such nozzles 38) is located in any 40 convenient position as to one side of the fluid-actuated nozzle 8, having a faced seat for a valve 39, mounted thereon at the inner end of a stem 40, passing out through a stuffing-box. The stem 40 is normally held outwardly by 45 compression-spring 41, tending to give full opening to nozzle 38 through the valve. The stem 40 is connected at 42 with arm 43, pivoted or otherwise suitably mounted at any convenient point and so arranged that its terminal or any other suitable bearing portion 50 is held in contact with the reduced portion of cam 44, thereby allowing the valve to open. This cam 44 is slidingly mounted on shaft 45 by means of a spline or other suitable sliding 55 connection and is adapted to be thrown backwardly and forwardly along shaft 45 in conformity with the varying speed of the governor A.

The weights of the governor are connected 60 with a sleeve 46 and also with the yoke 29 by pins 30, the yoke being connected with the valves 24 and 26 by stem 27 and 28, as already described. The sleeve 46 transmits 65 governor movement through lever 47, connecting-rod 48, and lever 49 to the sliding cam,

as will be readily understood and by reference to the above-cited application.

The cam 44 is adapted to act upon lever 43 and is provided with a variably-actuating raised portion adapted to cut off the supply 70 during a portion of each cam revolution or to entirely close or open the valves within the limits of the capacity of the nozzle which it controls.

For the purpose of utilizing the movement 75 of the sleeve 46 either upwardly or downwardly upon an increase or reduction from the normal speed (before the piston 20 and valve 17 become operative) the valves 26 and 24 are elongated, as shown in Fig. 2, and extend somewhat beyond ports 25 and 23. The valves 26 and 24 are thus inoperative as to releasing or admitting fluid through ports 25 and 23 until such elongated portions have passed the edge of the ports. During such 85 time the cam 44 is shifted to the right or left and will impart to valve 39 sufficient movement to entirely close or open it before the governing mechanism will act upon the main nozzle-valve 9. It will thus be seen that the 90 pulsating nozzle 38, controlled by valve 39, compensates for changes of load between any two adjacent pressure-actuated nozzles.

While the application of the invention may be made to a single-stage engine, it is obvious 95 that the same uniform regulation may be applied to two or more stages or engines of the multiple-expansion type, as shown in Figs. 2 and 4, by suitable valve-rod extension and fluid connections.

By means of the automatic regulation through nozzle 8 and of the supplemental intermittent regulation through nozzle 28 the speed of the engine is thus maintained constant and its equilibrium established.

It is obvious that various other constructions or arrangements of the valves may be used to control the admission of fluid to the turbine-vanes, and in Fig. 3 I have shown a plurality of nozzles 8', controlled by a single 100 valve 9', opening into a common chamber, which supplies the fluid directly to a greater number of nozzles by one valve, and it is obvious that the admission-nozzles may be designed and their number varied within the 105 province of the designing engineer to suit varying conditions or requirements of work. Thus the number of nozzles supplied from one valve, whether pressure or pulsating, should increase from one stage to the next 110 successively in order to accommodate the increased volume due to expansion. All such changes and variations are within the province of the designing engineer or skilled 115 mechanic and are to be considered as within the scope of the following claims.

I claim—

1. The combination with an elastic-fluid turbine, of a series of nozzles adapted to admit fluid successively, and a pulsating nozzle- 125 130

valve with means for controlling the supply of said nozzles in conformity with the speed of the engine.

2. The combination with an elastic-fluid turbine of a series of valves, pistons connected therewith, a supply of elastic fluid therefor, with means for controlling the supply thereof; and a supplemental pulsating nozzle-valve adapted to admit a variable volume of fluid to the vanes.

3. The combination with an elastic-fluid turbine, of a series of nozzle-valves adapted to admit fluid to the nozzles successively with means for actuating said valves, a valve adapted to admit a variable volume, a graduated cam adapted to impart movement to said valve, and means for varying the operative position of the cam according to the load of the engine.

4. In an elastic-fluid turbine, the combination with a series of nozzle-valves adapted to admit uniform volumes of elastic fluid to the vanes, of a fluid - supply - controlling valve adapted to admit a variable volume to the vanes, a graduated cam adapted to impart movement to said valve, and means for varying the operative position of the cam according to the load on the engine.

5. In an elastic-fluid turbine, the combination with a series of nozzle-valves adapted to admit uniform volumes of elastic fluid to the vanes, of a fluid - supply - controlling valve, adapted to admit a variable volume to the vanes, a graduated cam adapted to impart movement to said valve, a governor, and means connecting the governor with the cam whereby it is shifted in conformity with variations in the load of the engine.

6. In an elastic-fluid turbine, the combination of a series of nozzle-valves adapted to admit fluid successively, a series of pistons connected therewith, a pressure-supply-governing device, a governor connected with the pressure-supply-governing device, a nozzle controlled by a pulsating valve, a graduated cam adapted to impart movement to said valve, and means connecting the governor with the cam.

7. An elastic-fluid turbine, the combination of a series of nozzle-valves adapted to admit fluid successively, a series of spring-retracted pistons connected therewith, a cylinder provided with pressure-supply connections between the piston-chambers and the pressure-supply cylinder, a piston-valve mounted in the pressure-cylinder, actuating means therefor controlled by variations in the speed of the turbine, a valve, and a graduated actuating-cam therefor also controlled by variation in the speed of the turbine.

8. In an elastic-fluid turbine, the combination of a series of nozzles adapted to admit fluid successively, and a nozzle having an intermittent flow.

9. In an elastic-fluid turbine, a series of non-

pulsating nozzle-valves adapted to admit fluid successively in combination with a pulsating nozzle-valve.

10. In an elastic-fluid turbine, adapted to expand the fluid by stages, a series of nozzles for each stage, nozzle-valves therefor provided with pistons, and pressure connections between the pistons of successive stage-nozzles whereby the fluid - supply to the different stages is controlled simultaneously, and means independent of the pressure connections for retracting the pistons.

11. In an elastic-fluid turbine, adapted to expand the fluid by stages, a series of nozzles for each stage, nozzle-valves therefor provided with pistons, and pressure connections between the pistons of successive stage-nozzles whereby the fluid - supply to the different stages is controlled simultaneously and automatically in combination with stage-nozzles having an intermittent flow.

12. An elastic-fluid turbine adapted to expand the fluid by stages, nozzle-valves for each stage, fluid-actuated operating devices therefor, and pressure connections communicating with said devices throughout the different stages and with a source of pressure, with means controlling the supply therethrough in conformity with the speed of the engine.

13. An elastic-fluid turbine adapted to expand the fluid in stages and provided with successively-increasing numbers of nozzles for each succeeding stage, nozzle-valves therefor, fluid - actuated operating devices for said valves, and pressure connections communicating with said devices throughout the different stages and with a source of pressure.

14. An elastic-fluid turbine provided with a plurality of single series vanes, separate cylinders therefor within the walls of which cylinders the single series vanes rotate and whereby the fluid is expanded in stages, successively-increasing numbers of nozzles adapted to deliver the fluid thereto in proportion to the increasing volume of steam due to expansion, chambers communicating with said nozzles, controlling-valves therefor, fluid-actuated operating devices for the valves, and pressure connections communicating with said devices throughout the different stages and with a source of pressure.

15. An elastic-fluid turbine provided with a plurality of single series vanes adapted to expand the fluid by stages, and provided with a successively-increasing number of nozzles for each succeeding stage and supply-chambers communicating with said series of nozzles, with governor-controlled nozzle-valves adapted to admit the fluid to the nozzles in proportion to the load, and fluid-actuating operating devices therefor, with connections communicating therewith throughout the different stages and with a source of pressure.

16. An elastic-fluid turbine provided with a series of constant-volume nozzles and nozzle-

valves therefor, in combination with a nozzle provided with a pulsating valve adapted to admit fluid periodically.

17. An elastic-fluid turbine provided with a series of constant-volume nozzles and nozzle-valves therefor, in combination with a nozzle and a pulsating valve adapted to admit fluid periodically, the capacity of said valve being sufficient to compensate for variations in the capacity of any two loads between the nozzles.

18. An elastic-fluid turbine provided with a series of successively-supplied constant-flow nozzles in combination with an intermittently-supplied nozzle, adapted to compensate for variations in the load between the capacity of any two constant nozzles.

19. An elastic-fluid turbine provided with a

series of successively-supplied constant-flow nozzles in combination with an intermittently-supplied nozzle, adapted to supply a varying volume of fluid in addition to the volume furnished by the constant-flow nozzle.

20. An elastic-fluid turbine provided with a number of constant-flow nozzles, each of which supplies a fixed volume, in combination with an intermittent flow adapted to supply a variable volume.

In testimony whereof I affix my signature in presence of two witnesses.

WILLIAM S. ELLIOTT.
